UNITED STATES PATENT OFFICE.

MATHIAS JENSEN, OF ASTORIA, OREGON, ASSIGNOR OF ONE-HALF TO THE JENSEN CAN FILLING MACHINE COMPANY, OF SAME PLACE.

CAN-CAPPING MACHINE.

SPECIFICATION forming part of Letters Patent No. 448,047, dated March 10, 1891.

Application filed November 18, 1890. Serial No. 371,284. (No model.)

To all whom it may concern:

Be it known that I, MATHIAS JENSEN, of Astoria, in the county of Clatsop and State of Oregon, have invented a new and Improved 5 Can-Capping Machine, of which the following is a full, clear, and exact description.

The object of the invention is to provide a new and improved can-capping machine which is simple and durable in construction 10 and specially designed for automatically applying the caps on a certain class of can-bodies, such as made of uniform diameter and without exterior projecting seams.

The invention consists of a conveyer mounted 15 to swing vertically and longitudinally and adapted to carry the can-body forward to a stationary bed-mold, and a clamping-mold actuated from the said arm and adapted to clamp the can-body on the said stationary 20 bed-mold while the caps are forced onto its ends.

The invention also consists of certain parts and details and combinations of the same, as will be hereinafter fully described, and then 25 pointed out in the claims.

Reference is to be had to the accompanying drawings, forming a part of this specification, in which similar letters of reference indicate corresponding parts in all the figures.

30 Figure 1 is a side elevation of the improvement. Fig. 2 is a sectional side elevation of the same on the line $x-x$ of Fig. 3. Fig. 3 is a plan view of the improvement. Fig. 4 is a plan view of the conveyer and the mechanism 35 for operating the same. Fig. 5 is a transverse section of the improvement on the line $y-y$ of Fig. 3. Fig. 6 is a sectional side elevation of the improvement in different position from the one shown in Fig. 2, and Fig. 7 40 is a perspective view of one of the retaining-blocks for the caps.

The improved can-capping machine is mounted on a suitably-constructed main frame A, in which is journaled in suitable 45 bearings the transversely-extending main driving-shaft B, connected in the usual manner with suitable machinery for imparting a rotary motion to the said shaft in the direction of the arrow a' . On the main driving-shaft B is secured a gear-wheel B' in mesh at 50 opposite sides with the two gear-wheels B²

and B³, secured on the shafts C and C', respectively, also mounted to turn in suitable bearings in the main frame A and extending parallel with the main driving-shaft B. 55

At or near the middle of the shafts C and C' are formed the crank-arms C² and C³, respectively, pivotally connected with the ends of conveyer D, which receives a swinging motion by the said crank-arms when the main 60 driving-shaft B is rotated and the shafts C and C' are set in motion thereby. The conveyer D is provided on its top with two recesses D' and D², of which the recess D' is adapted to carry a can-body from a resting-place E' 65 onto the bed-molds E, between which the said conveyer D swings, and which are secured on longitudinally-extending plates F, supported on posts F', secured to the top of the main frame A. 70

The resting-places E' of the can-bodies are formed on the lower ends of upwardly-inclined bars E², secured to the inside face of the plates F, and on the upper end of which are placed the can-bodies to roll down to the 75 resting-place E'. On the opposite side of the fixed bed-molds E are arranged the downwardly-inclined bars E³, on which the can-body is placed by the conveyer D after the caps are put on, the capped cans then rolling 80 off of the machine. Each of the fixed bed-molds E is semicircular on top and onto it is adapted to pass a clamping-mold G, fitted to slide vertically in suitable bearings F², formed on the plates F. In the lower edge 85 of the clamping-mold G is arranged a semicircular opening corresponding to the semicircular opening or recess in the top of the bed-mold E, so that when the clamping-mold is in the lowermost position a full circular 90 opening is formed by the same and the bed-mold. This circular opening is somewhat less in diameter than the inside diameter of the caps to be put on the ends of the can-bodies.

The two clamping-molds G are connected 95 with each other by a pivot-pin G' passing through a lever H, extending rearwardly and pivotally connected by a pivot-pin H' with the upper end of a link H², pivoted at H³, between the insides of the plates F. The free 100 or forward end of the lever H carries a pivot-pin H⁴, on the ends of which are pivoted the

downwardly-extending rods I, secured at their lower ends in pivots I', mounted to turn near one of the ends of the conveyer D. When the main shaft B is rotated and the conveyer D swung, as previously described, the pivots I' and the rods I impart a swinging motion to the lever H, so that the clamping-molds G are moved vertically up and down in their bearings F², for the purpose hereinafter more fully described.

In order to bring the clamping-molds G into the proper position relative to the bed-molds E, the rods I are threaded at their lower ends and nuts I² and I³ screw at these lower ends on opposite sides of the pivots I', so that by adjusting the nuts the position of the lever H can be regulated to bring the clamping-molds G into the proper position. On each of the bed-molds E extends outwardly a cylinder J somewhat larger in diameter than the circular opening formed by the bed-mold and the clamping-mold previously described. Each cylinder J is secured or formed on the respective plate F, and is provided in its side with a slot J', through which the cap for the can-body can pass into the cylinder J.

Each slot J' registers with a chute K, inclined upwardly and secured to the outside of the respective plate F. The chute K is of such a width as to support the can-caps one behind the other and is inclined in such a degree that the caps successively roll into the cylinder J. The outer end of each cylinder J is somewhat reduced in diameter, and is reduced and contains a plunger or piston L, connected at its outer end with a lever N, fulcrumed on a suitable bracket projecting from the respective plate F. Each lever N is provided with a forked end, of which the prong N' passes into a slot L', formed in the respective plunger L. This prong on the swinging of the lever serves to move the plunger L outward in the cylinder J. In the other prong N² screws a set-screw N³, adapted to abut against the outer end of the plunger L, so as to move the latter inward, when the lever N receives a swinging motion. On the free end of each lever N is held a friction-roller O, engaging a cam-groove in a cam P, secured to the shaft C, previously mentioned. When the latter is rotated on revolving the main shaft B, as is previously described, the cams P impart a swinging motion simultaneously to the levers N, so that the plungers L, connected with the said levers, are moved simultaneously inward or outward in the cylinders J to force the caps onto the ends of the can-body, then clamped on the stationary bed-molds E. When the plungers L are in their outermost position, the slots J' in the cylinders are open, as is plainly illustrated in Fig. 5, to permit the lowermost cap in the respective chute K to pass into the respective cylinder.

65 An arm Q is provided for each chute K and arranged in line therewith and adapted to engage the front edge of the lowermost cap in

the chute, so as to prevent it from passing into the slot J' until the proper time arrives. Each arm Q is formed on a lever Q', pivoted 70 at Q² to the outside of the respective plate F, the free end of the said lever being engaged by the free end of an arm R, secured on a shaft R', extending transversely and mounted to turn in the two plates F. On the shaft R', 75 between the plates F, is secured an arm R², curved, as is plainly illustrated in Fig. 6, and adapted to rest on top of the can-body lifted by the conveyer D from the resting-place E' onto the stationary bed-molds E. Thus when 80 the upward swinging motion of the conveyer D takes place and a can-body is lifted from the resting-place E' upward, then the top of the can-body presses against the under side of the arm R², so that the shaft R' is turned 85 in its bearings, and the arms R act on the free ends of the levers Q', so that the latter swing upward, and their arms Q move out of the path of the respective lowermost cap held in the chutes K, so that this lowermost cap can 90 pass through the slot J' into the respective cylinder J. The arm R² drops into the position shown in Fig. 2 as soon as the respective can-body has been placed in the bed-molds, so that the arms Q quickly move downward to 95 engage the next-following caps in the chutes K to retain the said caps in place.

In order to retain the cap in place while moved by the respective plunger from the slot J' to the end of the can-body, a loose block S 100 is placed in the top of each cylinder J near its front end, the said block by its weight resting on top of the cap, thus holding the same in place during the movement of the cap through the inner end of the cylinder J. 105 The blocks are prevented from passing too far into the cylinders by transverse pins S, as shown in Fig. 1. These pins cross the slots in which the blocks S work and rest when the blocks are in their lowest or innermost positions on top of the cylinders J. The operation is as follows:

The can-bodies are fed one after the other down the inclined bars E², so that the lowermost body rests in the resting-places E'. The 115 chutes K are filled with caps, so that their openings extend inwardly, the lowermost caps being arrested by the arms Q. Now, when the main driving-shaft B is set in motion, a similar rotary motion is imparted to the shafts 120 C and C', which by their crank-arms C² and C³ impart a vertical and longitudinal movement to the conveyer D, which by its front recess D' engages the lowermost can-body in the resting-place E', lifts the same upward 125 and then by its forward longitudinal movement places the can-body into the semicircular recesses of the bed-molds E. By this upward movement of the conveyer and its can-body two caps are released in the chutes K, the 130 said caps passing through the slots J' into the cylinders J. When the can-body is in position on the bed-molds E, the conveyer D in its downward movement deposits it there and imparts

a downward swinging motion to the lever H, so that the clamping-molds G are forced downward to firmly engage the top of the can-body near the ends. The ends of the can-body 5 slightly project into the somewhat larger cylinder J. The outer faces of the bed-molds E are chamfered out to permit the inner ends of the cylinders J to extend under the lower half of the ends of the can-body, so that said cylinders 10 may guide the caps while entering onto the can-body. (See Fig. 5.) The molds G are also chamfered out like the bed-molds E, so that no parts thereof interfere with the caps while entering onto the can-body. The action 15 of the cams P forces the levers N to swing, so that the latter moves the plungers L inward, thereby forcing the caps in the cylinders J, so that the caps enter onto the ends of the can-body just as the molds G are on their lowermost 20 position and firmly clamping the can-body onto the bed-mold E. The conveyer D and the molds G are now again commencing to move upward, while the plungers L continue inward till the caps are properly forced onto 25 the can-body, and as the conveyer D moves farther upward its recess D' engages a new can-body and carries it over the front walls of the bed-molds E, while the recess D² engages the capped can and carries it over the rear walls 30 of the bed-mold E, and on the downward movement of the conveyer D the new can-body is lowered into the bed-mold E, while the capped can is lowered onto the bars E³, down which it rolls off the machine.

35 In order to regulate the inward movement of the plunger L so as to bring the caps into proper position on the ends of the can-bodies, the set-screws N³ are adjusted at the ends of the levers N, so as to accomplish the desired 40 result. A proper movement of the clamping-molds G is had by adjusting the nuts I² and I³ at the ends of the rods I previously mentioned.

I am aware that the mode of automatically 45 rounding and holding the can-body by means of clamping-molds while the cap is guided in a cylinder and applied to the can-body by means of a reciprocating plunger, as above described, is the same in principle as shown 50 in patent, No. 235,700, granted to George H. Pierce, December 21, 1880; but I deem that my invention as described above is an improved mode of applying that principle, and that it contains no inventions as claimed in 55 other patents, except the device for each can-body to release its own cap, which is here substantially the same as in my patent, No. 376,804, dated January 24, 1888.

Having thus fully described my invention, 60 I claim as new and desire to secure by Letters Patent—

1. In a can-capping machine, the combination, with the frame, a stationary horizontal bed-mold, and a clamping-mold above and 65 movable toward and from the stationary mold to press the can-body down thereon, of a ver-

tically and longitudinally swinging conveyer movable past the stationary mold to successively deposit and remove the can-body, substantially as set forth.

70

2. In a can-capping machine, the combination, with stationary bed-molds, of clamping-molds adapted to clamp a can-body onto the said bed-molds, a conveyer mounted to swing and adapted to carry the can-body onto the 75 said stationary bed-molds and also adapted to actuate the said clamping-molds, cylinders arranged in line with the said bed-molds, and plungers fitted to slide in the said cylinders and adapted to force the caps onto the ends 80 of the can-body held in the said bed-molds by the said clamping-molds, substantially as shown and described.

85

3. In a can-capping machine, the combination, with the frame, the horizontally-extending stationary bed-molds spaced apart, and vertically - reciprocating clamping - molds above the stationary molds to clamp the can-bodies down thereon, of a vertically and longitudinally swinging conveyer below and in 90 vertical alignment with the space between the two bed-molds to work therein and successively deposit and remove the can-body, and connections for operating the clamping-molds from the conveyer, substantially as set 95 forth.

4. In a can-capping machine, the combination, with stationary bed-molds, of a conveyer mounted to swing vertically and longitudinally and provided on top with two recesses, 100 of which one serves to lift the can-body onto the said stationary bed-molds and the other to remove the capped can from the said bed-molds, a resting-place arranged on one side of the said bed-molds and connected with inclined bars, and inclined bars arranged at the other side of the said bed-molds, substantially as shown and described.

105

5. In a can-capping machine, the combination, with stationary bed-molds and a can-body conveyer operating between the said bed-molds, of clamping-molds adapted to close onto the said bed-molds to hold a can-body in place thereon, cylinders arranged in line with the said bed-molds, and plungers fitted to 115 slide in the said cylinders and adapted to force the caps onto the projecting ends of said can-body while held by the said clamping-molds, substantially as shown and described.

110

6. In a can-capping machine, the combination, with stationary bed-molds and a can-body conveyer operating between the said bed-molds, of clamping-molds adapted to close onto the said bed-molds to hold a can-body in 125 place thereon, cylinders arranged in line with the said bed-molds, plungers fitted to slide in the said cylinders and adapted to force the caps onto the projecting ends of said can-body while held by the said clamping-molds, 130 and chutes adapted to carry the caps and opening into the slots formed in the said

cylinders in front of the said plungers when the latter are in their outermost position, substantially as shown and described.

7. In a can-capping machine, the combination, with a cylinder adapted to receive a cap, of a plunger fitted to slide in the said cylinder to move the cap in the same, and a vertically-movable block held in the said cylinder and adapted to rest on top of the cap when the latter is moved by the said plunger, substantially as shown and described.

8. In a can-capping machine, the combination, with stationary bed-molds, of clamping-molds adapted to clamp a can-body onto the said bed-molds, an arm mounted to swing and adapted to carry the can-body onto the said stationary bed-molds and also adapted to actuate the said clamping-molds, cylinders arranged in line with the said bed-molds, plungers fitted to slide in the said cylinders and adapted to force the caps onto the ends

of the can-body held in the said bed-molds by the said clamping-molds, and means, substantially as described, for imparting motion to the said movable parts, substantially as shown and described.

9. In a can-capping machine, the combination, with stationary bed-molds and clamping-molds arranged in conjunction therewith for holding a can-body in place, of cylinders extending in line with the said molds, plungers fitted to slide in the said cylinders, and levers having swinging motion and each provided with a forked end, of which one prong engages the slot in the respective plunger and the other prong carries a set-screw adapted to engage the outer end of the plunger, substantially as described.
